BOBBIN CARRIER FOR BRAIDING
MACHINES

Robert A. Seger, Louisville, Ky.

Application July 17, 1936, Serial No. 91,045

5 Claims. (Cl. 96—13)

This invention relates to a machine for braiding solid cord, such as window sash cord, clothes-lines, trolley cords or any other non-kinkable rope wherein the threads are braided. It is also applicable to the braiding of fishing lines, shoe 5 strings, wire insulation and the like.

As is well understood in the art, such machines are provided with horizontally rotating plates carrying a plurality of bobbins vertically and rotatably disposed thereon, which in turn carry the 10 threads to be braided in forming cord or the like. Such carriers are so formed as to rotatably support the bobbins in vertical position and carry them in an irregular but generally circular path 15 usually in a clockwise direction about the machine and central strand, if any, which passes upwardly therethrough, one carrier being caused to pass inwardly about the two preceding carriers while they remain stationary so that the thread 20 will pass under the two preceding threads, whereby by a series of lock stitches will be formed. As the lock stitches are formed about the central thread, if any, they are drawn therewith through a former, the function of which is to permit the 25 desired tension on the thread to be maintained, thus providing an evenly braided cord.

The invention resides in mounting a check or 30 steadyng member on the braiding machine in association with the carrier and bobbin mounted thereon. Due to the looseness of the carrier mounting in respect to the table, particularly 35 after wear and in operating at high speeds, there is a forward thrust or movement of the carrier occurring as it is set out on the plate. This results in a reciprocating movement of the bobbin and also causes some backlash which results 40 in kinking of the yarn and other undesirable actions. It is, therefore, the purpose of this invention to provide such a check and steadyng 45 member in the form of a rubber or spring guard for minimizing or substantially eliminating the undue thrust of the carrier occurring as it is set out on the plate. Such check steadies the carrier at this point and frictionally resists any backlash movement, thereby preventing kinking of the yarn or undue stretching and releasing thereof.

The full nature of the invention will be understood from the accompanying drawings and 50 the following description and claims:

Fig. 1 is a front elevation of the carrier in operating position. Fig. 2 is a partial illustration thereof shown in inoperative position. Fig. 3 is the same as Fig. 1, showing a side elevation. Fig. 54 is the same as Fig. 3 showing a central ver-

tical section therethrough. Fig. 5 is a fragmental front view showing the aperture and groove with the spring broken away. Fig. 6 is a plan view of the braiding machine table indicating diagrammatically one position of the bobbins. Fig. 7 is a side elevation taken on the line 7—7 of Fig. 6.

In the drawings there is shown a bobbin carrier supported for operation in the usual manner well known in the art by a cord braiding machine having a center plate 10, internal gear 11 and a top plate 12, the center and top plates being provided with their usual cam grooves for moving the several carriers mounted thereon relative to each other for effecting the braiding operation.

The carrier is L-shaped having a supporting base 13 slidably mounted upon the upper surface of the top plate 12. Said base is connected to a flange 14 spaced from the underside of the top plate by a cam member 15 operating in the cam grooves of the top plate 12. Extending downwardly through the internal gear 11, there is a spindle 16 having a flange 17 and a cam member 18 extending downwardly therefrom into the cam grooves of the center plate 10. Thus, as the plates 10 and 12 are rotated in the operation of the machine, the cam members 15 and 18 will cause the carrier to travel in the desired braiding relation with the other carriers.

Extending upwardly from the base 13 there is a bobbin carrying spindle 19, which carries the bobbin 20 with the usual upper and lower end disks 21 between which the thread 22 is wound. Formed integrally with the base 13 and extending upwardly vertically therefrom to one side of the spindle 19 and so spaced as to clear the bottom, there is a standard 23 having a passage 24 formed therein through which the thread is drawn, said passage communicating with an upwardly extending V-shaped groove 25 for guiding the thread in its upward direction and freely permitting the passage through it of any knots in the thread. At the upper end of the standard there is an apertured barrel 26 for feeding the thread directly from the carrier to the former on the machine.

Intermediate the passage 24 and barrel 26, there are in-and-out passages 24a and 24b formed in the standard 23, said passages being smoothed and rounded for providing frictional resistance to the passage of the thread therethrough, but having no sharp corners or edges such as would interfere with the passage of knots or cause any undue wear or strain upon the yarn.

Mounted upon the outer face of the standard 23 there is a flat bowed sheet metal spring 27

which spans the aperture 24 and groove 25. Said spring is adjustably held against the standard by an adjusting screw 28. The opposite ends of the spring bear against the surface of the standard, the upper end being flattened so as to be engaged by the thread passing through the groove and between the adjacent surfaces of the spring and standard, as indicated at 29. By means of the spring 27 frictional resistance to the passage of the thread is provided, and varied by the adjustment of the screw 28 so as to control the tautness of the thread passing through the barrel 26 to the former of the machine.

The carriage is provided with a safety device 15 construction and gravity actuated throughout member 30 slidably mounted upon the standard, provided with a U-shaped wire hanger 31 which extends upwardly and under the thread so that the tautness of the thread between the former and the spring, passing through the barrel 26, maintains the member 30 in its elevated position. Upon breaking of the thread, however, the member 30 will be released so that it will drop by gravity to the position shown in Fig. 2, in which 20 position it will engage a trip lever on the machine, not shown, which will stop the operation of the machine in the well-known manner understood in the art.

By reason of this construction, the carrier, 30 so far as the threading thereof, spring and weight attachments, and ratchet release mechanism are concerned, is greatly simplified. The resistance to the movement of the thread for maintaining the desired tautness and eliminating any slack 35 is entirely controlled by the tension of the spring 27 which is adjustable so that any amount of resistance and tautness may be readily obtained. Furthermore, the resistance to the passage of the thread and its tautness is constant, as distinguished from intermittent as heretofore, and the 40 character of the resistance, and particularly the arrangement of the several apertures, readily permits of any knots in the thread passing therethrough, under the spring 27 and through the barrel without danger of fouling and breaking.

As illustrated in Fig. 6, the braiding machine is provided with twelve carriers. In the position of the carriers illustrated therein, certain pairs 50 are positioned at the "set out" point, or the extreme outer position. In the rapid rotation of the machine, the action is such that the carriers and the bobbins supported thereon are thrust with substantial force into the set out position, which results in a rocking action occurring due to looseness between the base portion of the carrier and the cam slots and supporting surfaces 55 of the machine. Unless restrained, this rocking or thrust action has the effect of causing backlash, as well as stresses and strains upon the yarn. For restraining the bobbins at their respective set 60 out points, there is provided a resilient band 32 extending about the periphery of the machine and supported upon the rollers 33 mounted on spindles 34 which are bolted upon the projection 65 35 extending radially from the fixed marginal plate 36 of the machine. This band may be in the form of heavy rubber or spring material such

as will give with the impact of the bobbin when the carrier reaches the extreme set out point, but which, by its tension, will restrain and steady the bobbin and carrier and frictionally resist rotation thereof to prevent backlash. By this means, freedom of movement of the bobbin and carrier is permitted while thrust or rocking and backlash are prevented or reduced to a minimum of action, such as will avoid kinking, and undue stretching and releasing.

The invention claimed is:

1. A braiding machine including a plurality of carriers, each being adapted to receive a thread carrying bobbin, a support, means on said machine for moving said carriers to different positions on said support for effecting the braiding of the thread carried by the bobbins, and means on said support for resisting rocking movement of the carriers and their respective bobbins upon being moved to their extreme set out positions.

2. A braiding machine including a plurality of carriers, each being adapted to receive a thread carrying bobbin, a support, means on said machine for moving said carriers to different positions on said support for effecting the braiding of the thread carried by the bobbins, and means on said support adapted to be engaged by the bobbin for yielding resisting outward thrust thereof and frictionally resisting rotary movement.

3. A braiding machine including a plurality of carriers, each being adapted to receive a thread carrying bobbin, means on said machine for moving said carriers to different positions for effecting the braiding of the thread carried by the bobbins, and means for frictionally and yieldingly engaging the bobbin upon the bobbin being moved to its extreme set out position for steady- 35 ing the carrier and preventing rocking action 40 while resisting free rotation of the bobbin.

4. A braiding machine including a plurality of carriers, each being adapted to receive a thread carrying bobbin, means on said machine for moving said carriers to different positions for effecting the braiding of the thread carried by the bobbins, and a band of yielding material extending about said machine in position to be engaged by the respective bobbins upon their being moved to extreme set out position for resisting 45 undue rocking movement thereof and preventing 50 backlash.

5. A braiding machine including a plurality of carriers, each being adapted to receive a thread carrying bobbin, means on said machine for moving said carriers to different positions for effecting the braiding of the thread carried by the bobbins, a plurality of supports spaced about the periphery of said machine and secured thereto, and a resilient band carried by said supports so as to extend tangentially to the rotary movement 60 of said machine between said supports against which said bobbins engage upon their movement to extreme set out position, said band yieldingly resisting further movement of said bobbins and 65 frictionally preventing backlash thereof.

ROBERT A. SEGER.
